UNITED STATES PATENT OFFICE.

LOUIS T. ANDERSON, OF CARROLL, IOWA.

TRACE-CARRIER.

SPECIFICATION forming part of Letters Patent No. 294,952, dated March 11, 1884.

Application filed August 24, 1883. (Model.)

To all whom it may concern:

Be it known that I, LOUIS T. ANDERSON, of Carroll, in the county of Carroll and State of Iowa, have invented a new and Improved 5 Trace-Carrier or Buckle, of which the following is a full, clear, and exact description.

The object of my invention is to provide a new and improved combination trace-carrier and buckle for harnesses.

10 The invention consists in a buckle-frame provided with a cross-piece having a pin or tongue, and with a hook having a projecting guard. The pin serves to hold the buckle to the hip-strap, the hook serves to hold the cock-eye of the trace, and the guard serves to prevent the horse's tail or the lines from catching in the hook.

Reference is to be had to the accompanying drawings, forming part of this specification, 20 in which similar letters of reference indicate corresponding parts in all the figures.

Figure 1 is a longitudinal elevation of my improved combined trace-carrier and buckle, showing how it holds the trace and how it is fastened. Fig. 2 is a longitudinal sectional view of the same on the line $x-x$, Fig. 1. Fig. 3 is a perspective view of my improved combined trace-carrier and buckle.

A buckle-frame, A, is provided with downwardly-curved side bars united by a cross-plate, B, having an upwardly-projecting pin or tongue, C. At one end the buckle-frame is provided with a curved hook, D, the end of the prong of which is bent upwardly toward the shank 35 to form an eye, the diameter of which is greater than its opening D'. From the outer end of

the curved part of the hook a guard-prong, E, projects. The cockeye F is secured to the trace G in the usual manner, and the hip-strap H is passed through the frame A through the 40 ring J, suspended from the back-strap K, and the end of the strap H is passed back through the buckle-frame and under the upper part of the strap, as shown in Fig. 2, the pin or tongue C passing through both parts of the strap H, 45 as shown, whereby the frame A is held in the said strap without sewing. The guard E rests on the hip-strap H and prevents the horse's tail or the lines from catching on the hook. The cockeye F is turned to be at right angles 50 to the hook-prong, and its thinner inner part is passed through the opening in the hook, and then the cockeye is turned to be parallel with the hook, and so that its thicker outer part will be in the hook. Then the cockeye can- 55 not be removed by jolts, &c., but can only be removed from the hook by turning it until its thinner part can be passed through the opening D' of the hook.

Having thus fully described my invention, I 60 claim as new and desire to secure by Letters Patent—

The buckle-frame A, provided with a cross-piece, B, having a pin or tongue, C, and with a hook, D, having a projecting guard, E, said 65 hook and guard being arranged to extend in opposite directions, substantially as herein shown and described.

LOUIS T. ANDERSON.
